FIRE EXTINGUISHING SYSTEM

Scott E. Allen, Los Angeles, Calif., assignor, by
mesne assignments, to C-O-Two Fire Equipment
Company, Newark, N. J., a corporation
of Delaware

Application October 18, 1932, Serial No. 638,286

16 Claims. (Cl. 169—11)

My invention relates to fire extinguishing methods and apparatus in which carbon dioxide or other highly compressed fluid extinguisher is employed.

5 An object of the invention is to provide a fire extinguishing system particularly adapted for the protection of airplane and airship hangars, or for a deck on which aircraft are supported. Owing to the highly combustible nature of the materials 10 of which aircraft are usually built, it is essential that the fire be extinguished immediately. In the case of airplanes, for instance, the wings, fuselage, rudders, elevators, etc. are often made merely of wood covered with linen, silk, cotton 15 fabric or the like, treated with lacquer to present a smooth surface to the air currents, and for protecting such highly combustible material distributed about a hangar which in some cases is very large, the ordinary fire extinguishing systems 20 are entirely inadequate. It is impracticable to attempt to protect the aircraft by discharge of fire extinguishing fluid from the walls of the hangar since such protection could not be extended more than a few feet from the walls. On 25 the other hand, if the fire extinguishing fluid were discharged from the rafters or ceiling of the building it would have to oppose the air currents set up by the fire and before sufficient of the extinguisher could be introduced in the hangar to 30 smother out the flames, the damage would have been accomplished.

In the case of an airplane afire, the blaze may 35 be shielded by the wings so that a gaseous extinguisher discharged from above would not reach the blaze and would not prevent the latter from being fed with air sucked up by the fire. Since the air currents usually rise to the fire, it is preferable to discharge the extinguisher from beneath so that the gas will be carried up to the blaze 40 by the natural draft produced by the fire.

An object of my invention, therefore, is to provide a system employing carbon dioxide or other highly compressed extinguishing fluid in which the fluid is discharged in the form of a gas from 45 outlets in the floor of the hangar or other enclosure.

In a copending application Serial No. 607,062, filed April 23, 1932, I describe a fire extinguishing system of this general character having floor outlets with covers normally closing the outlets but adapted to be opened by the gas pressure developed in the outlets. The outlets are in the form of expansion chambers and it will be obvious that with large expansion the pressure 55 might not be sufficient to blow the cover clear of

the outlet. In such case, as soon as the pressure was relieved by partial opening of the outlet the cover would drop back to closed position, only to open as soon as the pressure was again built up. Thus the cover would flutter over the outlet 5 and the gas instead of pouring out continuously would be discharged intermittently, so that volumes of air might be sucked into the fire in alternation with puffs of the extinguisher.

An object of the present invention is to avoid 10 any possibility of fluttering and to provide for positive opening of the covers by means which are not affected by pressure conditions in the expansion chambers.

Another object of the invention is to provide 15 for horizontal spread of the fire extinguisher along the floor.

Another object of the invention is to provide means for raising a cover bodily to such position that it will not interfere with the lateral spread 20 of extinguisher.

Another object of the invention is to provide means for supporting the cover when opened in such position as to baffle the discharge of gas and compel it to spread horizontally along the floor. 25

Other objects and advantages of my invention will appear in the following description of a preferred embodiment and of a modification thereof and thereafter the novelty and scope of the invention will be pointed out in the claims. 30

In the accompanying drawing:

Figure 1 is a view in cross-section of a hangar equipped with my improved fire extinguishing apparatus, showing a plurality of floor outlets adapted to be connected with a source of extinguishing fluid; 35

Fig. 2 is a detail view in vertical section of a preferred form of floor outlet; and

Fig. 3 is a similar view of another form of floor outlet. 40

A hangar protected by my improved fire extinguishing apparatus is indicated in Fig. 1 by the numeral 10. In this hangar are shown a plurality of airplanes 11. At a suitable point outside of the hangar there is a supply of fire extinguishing fluid preferably stored in a battery of containers. However, only one of the containers is shown at 12 in the drawing. A suitable discharge mechanism 13 is provided for releasing the fluid from the containers and discharging it into a pipe system 14. This pipe system passes under the floor 15 of the hangar and is provided with a plurality of nozzles 16 that open respectively into expansion chambers embedded 45 in the floor 15. 50

Each expansion chamber, as shown in Fig. 2, comprises a casing 17 formed with a hemi-spherical bottom 18. The nozzle 16 opens through the bottom 18 and projects slightly into the chamber. 5 A baffle plate 19 is supported on studs 20 above the nozzle so that the jet of gas issuing from the nozzle will strike the plate 19 and spread around it. As a result the gas will be considerably expanded in the chamber 18 and will discharge from 10 the top of the chamber at greatly lowered velocity. The casing 17 is normally closed by a lid 21 which lies flush with the floor. However, when fire extinguishing fluid is led into the expansion chamber the lid is opened by certain fluid actuated 15 mechanism, as will now be described.

A branch pipe 22 leads from the main pipe system 14 and passes through the side wall of the casing 17. This branch pipe opens into the lower end of a cylinder 23 which is carried by a spider 20 24 suitably supported on lugs 25 projecting from the inner face of the casing 17. Fitted to slide within the cylinder is a plunger 26 which has a stem 27 affixed at its upper end to the lid 21. The plunger 27 passes through a bushing 28 25 threaded into the cylinder and this bushing serves as a guide for the stem and also as a stop to limit the rise of the plunger. A flat spring 29 is secured to the stem 27 and projects slightly therefrom, as shown in Fig. 2, so that when the plunger 30 is forced upward to raise the lid 21 the spring 28 will engage the bushing 28 frictionally and support the cover in raised position.

In operation, whenever a fire is detected the discharge mechanism 13 is operated and extinguishing fluid is admitted to the piping system 35 14. The fluid being under high pressure will force the plungers 26 upward, raising all of the lids 21 approximately to the position shown in broken lines in Fig. 2. At the same time the fluid will 40 be discharged from the nozzle 16 into the expansion chambers and will discharge from said chambers at a considerably reduced velocity into the hangar. Because the lids 21 are supported directly above the outlets they will act as baffles 45 to prevent a directly vertical rise of the gas. Instead the gas will have to spread horizontally along the floor and it will be drawn by suction into the fire, smothering the same. After the fire is extinguished the lids may be restored to their 50 closed position by merely stepping on them and forcing them down to the full line position shown in Fig. 2. Thereafter, another set of containers may be supplied to replace the discharge containers 12 and the apparatus will then be ready 55 for another fire.

The discharge device shown in Fig. 3 is similar to that shown in Fig. 2 as regards the jet and general form of the container. However, the lid instead of being raised bodily, is hinged and must 60 be swung to open position. As illustrated, the casing 30 of the expansion chamber is sunk into the floor 15 of the hangar and a closure member 31 for the chamber is connected by hinge 32 to the casing 30, in such manner that normally it 65 lies flush with the floor. The piping system 14 and nozzle 16 admit fluid extinguisher into the casing 30 and the jet of extinguishing fluid is baffled by a plate 19 in the same way as in the structure illustrated in Fig. 2. The casing 30 70 differs from the casing 17 in having a cylinder 33 formed against its side wall. Slidably in this cylinder is a plunger 35, and a rod or stem 36 pivotally connected to the plunger bears against the under face of the lid 31 close to the hinge 32. 75 The rod passes through a collar or bushing 37

threaded into the upper end of the cylinder and secured at desired adjustment by a set screw 38. A branch line 39 leads from the main piping system 14 to the lower end of the cylinder 33.

In operation when extinguishing fluid is admitted in to the pipe 14 a portion of the fluid enters the cylinder 33, through branch pipe 39, raising the plunger 33 and swinging the lid open. The aperture in the collar 37, through which the rod 36 passes, is not in axial alignment with the plunger but is shifted slightly toward the hinge (i. e. toward the right as shown in Fig. 3). Hence the rod which is pivoted centrally on the plunger is also inclined toward the hinge, and as the plunger rises such inclination increases, and the upper end of the rod will continue to exert thrust against the lid until the latter has passed vertical position, as shown by broken lines at A, after which the lid will continue its swing by gravity until it lies on the floor 15, as shown by broken lines at B. The collar 37 serves not only as a guide to direct the rod 36 but also as a stop for the plunger 33, being provided with a depending flange 40 against which the plunger bears at the upper limit of its stroke.

It will be noted that with either of the opening devices it is not necessary to wait until sufficient pressure is developed in the outlet chamber to blow the lid off the chamber. Instead, the lid is raised positively and to a fixed position by the pressure of the fluid in the system independently of pressure conditions in the expansion chambers. The plungers 26 and 25 need not fit snugly in their respective cylinders because there is plenty of pressure available to open the lids.

My invention is peculiarly adapted for the protection of hangars, but it is equally applicable to other enclosures and also to open areas, such as the decks of ships, air-craft carriers, etc., on which highly inflammable cargo or apparatus is 40 stored. The term "floor" as used in the claims is to be interpreted as comprising any supporting surface.

While I have described a preferred embodiment 45 of my invention and a modification thereof I wish it to be understood that these are to be taken as illustrative and not limitative of my invention and that I reserve the right to make such changes in form, construction, and arrangement of parts as fall within the spirit and scope 50 of the following claims.

I claim:

1. In a fire extinguishing system for a space having a floor, a source of highly compressed extinguishing fluid, a plurality of cup-shaped discharge outlets opening through said floor, a cover for each outlet, opening means adapted to be actuated by fluid pressure to open each cover, a nozzle at the bottom of each outlet, and means leading said extinguishing fluid from said source to the nozzles and separately to said opening means.

2. In a fire extinguishing system for a space having a floor, a supply of highly compressed extinguishing fluid, a distributor pipe leading therefrom, a plurality of cup-shaped discharge outlets leading from the pipe through said floor, means for releasing said fluid into said pipe, a closure for each outlet, fluid actuatable means for opening each closure, and a connection from said distributor pipe to each of said fluid actuatable means whereby fluid from the discharge pipe will actuate the latter means.

3. In a fire extinguishing system for a space having a floor, a supply of highly compressed extinguishing fluid, a plurality of cup-shaped dis-

charge outlets opening through the floor, a cover for each outlet, a cylinder at each outlet, a plunger operable therein, an operative connection from the plunger to the cover, and means for discharging said fluid from the supply into the bottom of each outlet and simultaneously into said cylinders to raise the plungers and open the covers.

4. In a fire extinguishing system for a space having a floor, a supply of highly compressed extinguishing fluid, a distributor pipe leading therefrom, a plurality of discharge outlets leading from the pipe through said floor, means for admitting said fluid into said pipe, a lid normally closing each outlet, fluid actuatable opening means for raising the lid bodily above the outlet, and a separate fluid connection from the distributor pipe to said opening means to actuate the latter when fluid is admitted into said pipe.

5. In a fire extinguishing system for a space having a floor, a supply of highly compressed extinguishing fluid, a distributor pipe leading therefrom, a plurality of discharge outlets leading from the pipe through said floor, means for admitting said fluid into said pipe, a lid normally closing each outlet, fluid actuatable opening means for raising the lid bodily to a position spaced above the outlet, a fluid connection from the distributor pipe to said opening means to actuate the latter when fluid is admitted into said pipe, and means for retaining the lid in said position over the outlet.

6. In a fire extinguishing system for a space having a floor, a supply of highly compressed extinguishing fluid, a plurality of discharge outlets opening through said floor, a lid for each outlet, means for leading said extinguishing fluid to said outlets, means actuated by pressure of the extinguishing fluid for raising the lid bodily to a position spaced above the outlet, and means for retaining the lid in said position.

7. In a fire extinguishing system, a floor outlet for highly compressed fire-extinguishing fluid, comprising a casing, a nozzle projecting into the casing through the bottom thereof and terminating adjacent the bottom of the casing, a cover normally closing the top of the casing, a vertical cylinder closed at the bottom and supported centrally in the casing, a plunger in the cylinder, said plunger having a stem fixed at its upper end to the cover, means for conducting said fluid into the nozzle and also into the cylinder below the plunger, and a stop for limiting the rise of the plunger under pressure of said fluid.

8. In a fire extinguishing system, a floor outlet for highly compressed fire-extinguishing fluid, comprising a casing, a nozzle projecting into the casing through the bottom thereof and terminating adjacent the bottom of the casing, a cover normally closing the top of the casing, a vertical cylinder closed at the bottom and supported centrally in the casing, a plunger in the cylinder, said plunger having a stem fixed at its upper end to the cover, means for conducting said fluid into the nozzle and also into the cylinder below the plunger, a stop for limiting the rise of the plunger under pressure of said fluid, and a detent for retaining the plunger in raised position.

9. In a fire extinguishing system, a floor outlet for highly compressed fire extinguishing fluid, comprising a casing, a nozzle projecting into the casing through the bottom thereof and terminating adjacent the bottom of the casing, a cover normally closing the top of the casing, a vertical cylinder closed at the bottom and supported centrally in the casing, a plunger in the cylinder,

said plunger having an upwardly extending stem constructed and arranged to raise the cover when the plunger is raised, means for conducting said fluid into the nozzle and also into the cylinder to raise the plunger and the cover, and friction means for retaining the plunger in raised position.

10. In a fire extinguishing system, a floor outlet for highly compressed fire extinguishing fluid, comprising a casing, a nozzle projecting into the casing through the bottom thereof and terminating adjacent the bottom of the casing, a cover normally closing the top of the casing, a vertical cylinder closed at the bottom and supported centrally in the casing, a plunger in the cylinder, said plunger having a stem connected at its upper end to the cover, means for conducting said fluid into the nozzle and also into the cylinder to raise the plunger and the cover, a bushing in the upper end of the cylinder through which the stem passes, said bushing serving to limit the rise of the plunger, and a spring on the stem coacting with said bushing to frictionally retain the plunger in raised position.

11. In a fire extinguishing system, a floor outlet for fire extinguishing fluid, comprising a casing, a nozzle projecting into the casing through the bottom thereof and terminating adjacent the bottom of the casing, a hinged cover normally closing the top of the casing, a vertical cylinder in the casing and adjacent the cover hinge, said cylinder being closed at the bottom, a plunger in the cylinder, a rod pivotally connected to the plunger and bearing against the cover, means for conducting the fire extinguishing fluid into the nozzle and also into the cylinder to raise the plunger, and means for arresting the plunger after it has risen far enough to swing the cover past the vertical position.

12. In a fire extinguishing system, a floor outlet for fire extinguishing fluid, comprising a casing, a nozzle projecting into the casing through the bottom thereof and terminating adjacent the bottom of the casing, a hinged cover normally closing the top of the casing, a vertical cylinder in the casing and adjacent the cover hinge, said cylinder being closed at the bottom, a plunger in the cylinder, a rod pivotally connected to the plunger at a central point thereof and bearing against the cover, means for conducting the fire extinguishing fluid into the nozzle and also into the cylinder to raise the plunger and swing the cover open, an apertured guide at the upper end of the cylinder through which the rod passes, the aperture of said guide departing from axial alignment with the plunger in the direction of the cover hinge, whereby the plunger will bear against the cover until the latter has swung past the vertical position, and means for arresting the plunger after it has risen far enough to swing the cover past the vertical position.

13. The method of extinguishing a fire in a space having a floor, which consists in discharging at various points distributed throughout the floor jets of fire extinguishing fluid liquefied under pressure, expanding the liquid into gas and discharging the gas horizontally along said floor, whence it may be drawn into the fire by suction produced by the fire.

14. A method of extinguishing a fire in a space having a floor which consists in discharging jets of fire extinguishing fluid liquefied under pressure, expanding the liquid into gas, and discharging the expanded gas through the floor and hori-

zontally along the floor, whence it may be drawn into the fire by suction produced by the fire.

15. The method of extinguishing a fire in a space having a floor which consists in discharging below the floor level and at a plurality of points distributed throughout the floor jets of fire extinguishing fluid liquefied under pressure, expanding the liquid into gas, and discharging the gas horizontally in all directions along the floor, whence it may be drawn into the fire by suction produced by the fire.

16. In a fire extinguishing system for a space having a floor formed with a plurality of recesses, a cover for each recess, opening means adapted to be actuated by fluid pressure to open each cover, a source of highly compressed fire extinguishing fluid, means for discharging the fluid into the bottom of each recess and separate means for leading a part of the fluid from said source to each opening device to open the covers.

10

SCOTT E. ALLEN.
